Re. 15,834

UNITED STATES PATENT OFFICE.

CHRISTIAN BERGER, OF NEW YORK, N. Y., ASSIGNOR TO COMPUTING-TABULATING-RECORDING COMPANY, A CORPORATION OF NEW YORK.

MEASURING APPARATUS.

Original No. 1,295,842, dated March 4, 1919, Serial No. 258,329, filed October 16, 1918. Application for reissue filed September 3, 1920. Serial No. 408,091.

To all whom it may concern:

Be it known that I, CHRISTIAN BERGER, a citizen of the United States, residing at New York city, in the county of New York 5 and State of New York, have invented certain new and useful Improvements in Measuring Apparatus, of which the following is a specification, reference being had therein to the accompanying drawing.

10 This invention relates to measuring apparatus, and more particularly to apparatus for measuring the weight of articles such as merchandise, and a particular instance in which this invention possesses utility is the so called automatic weighing machine having a relatively movable chart of tables or scales upon which the weight or even the sales price of the commodity upon the scales is directly indicated. The invention is applicable to the various types of such apparatus now well known. In one type the chart of tables or scales consists of a rotary cylinder on which the tables are impressed by printing or otherwise inscribed, this cylindrical chart being viewable by the salesman at one side and by the customer at the other side, and I show this type as an illustration of the utility of the invention.

15 The general object of the present invention is to improve the efficiency and convenience of measuring apparatus especially of the kind mentioned. The general plan is to have over the chart's area, two complete sets of tables or inscriptions, of different colors or kinds, and to view the same by different lights, so that either one is made apparent, the other disappearing; thus effectively doubling the useful area of the chart. When duplicate tables are used they will 20 usually be viewed simultaneously from different points; but two tables, corresponding, or otherwise related, may be used, to be viewed at different times or selectively by the salesman, obvious uses being to print dollars and cents in one color, and shillings 25 and pence in the other, or weights up to a certain limit in one color and beyond it in the other, giving a double range of readings and prices.

30 A particular object is to afford a measuring machine with a relatively movable chart, and which can be consulted so as to disclose either of the two tables to an observer, or consulted simultaneously by two persons

from different or opposite viewpoints so as 55 to correctly give the same reading or indication at each side, and without confusion or other inconvenience.

Another object is to enable the utilization 60 of the entire surface of the chart or rotary cylinder for the purpose of indicating measurements readable at different times or to persons at both sides, yet without confusion from the presence of the numbers or characters not to be read.

65 Other and further objects and advantages will be elucidated in the hereinafter following description of an embodiment of the present invention, or will be clear to those skilled in the art.

70 To the attainment of the above objects and advantages, the present invention consists in the novel measuring apparatus and the novel table, scale or chart herein illustrated or described, as well as the various 75 described features of combination, arrangement and detail.

In the accompanying drawings forming part hereof, Figure 1 is a side elevation showing a suitable measuring apparatus, 80 namely, an automatic weighing machine of usual commercial form and embodying the present invention.

Fig. 2 is a left elevation of the upper part 85 of the same, showing especially the casing and a part of the movable cylindrical chart contained therein.

Fig. 3 is a diagrammatic central cross-section of the parts seen in Fig. 2.

Fig. 4 is a diagrammatic perspective view 90 of the cylindrical tabular chart, with many of the numerals or entries omitted and those that are shown exaggerated in size and arrangement. The first series of numbers in this diagram are indicated completely 95 around the periphery of the chart at the points where they would not be seen in the perspective view, for the purpose of explanation.

Figs. 5 and 6 are optical diagrams showing 100 the action of the light and the effect of the medium or screen.

Fig. 7 is an enlarged view of the inscription on the chart at the left side.

Fig. 8 is a similar view of the corresponding inscription observed by the person at the opposite or righthand side.

Fig. 9 shows how the inscription of Fig.

7 appears to the observer at the left by the use of the medium or screen at that side, and Fig. 10 correspondingly shows how the inscription of Fig. 8 appears to the observer 5 at the right by the use of the medium at that side.

Figs. 11, 12 and 13 indicate modified embodiments of the invention adapted to give analogous results.

10 I will first describe some of the features of the particular type of measuring or weighing apparatus to which for illustration I have shown the present invention applied. Referring to Fig. 1, within the base 15 and 15 standard 16 is located suitable weighing mechanism, the details of which per se form no part of the present invention. Above the base is the scale pan or platform 17, upon which is shown a commodity or article of 20 merchandise 18, which is the subject of sale, and the weight and price of which is to be determined. At the top of the standard is a casing 19, containing the relatively movable and preferably rotary cylindrical chart 25 20, mounted preferably on a horizontal axis by any suitable fixtures. By this arrangement the cylindrical chart 20 bearing the inscriptions or numerals 21 is viewable from the two opposite sides of the sales counter 30 by the customer and the salesman, respectively. At each side of the casing 19 is provided with an opening surrounded by a hood or frame 22, which may contain a plate of glass 23, so that the tabular matter or 35 scales can be easily seen. The scales may be inspected by the general illumination or daylight, or in some cases it is preferable to provide special lamps 24.

Normally, when no article is on the scale 40 pan, the rotating chart or cylinder 20 stands with each of its scales at zero, and as an index to judge the correct reading a distinctive horizontal or zero line 25 is suitably inscribed on the plate glass 23 or otherwise. 45 The operation in determining the price of a quantity of material placed in the scale pan may be as follows. The interior mechanism causes the rotation of the cylindrical chart 20 until it comes to balance at the 50 proper adjustment. As shown in Fig. 4, this indicates a reading of 5, which means five cents if the scale system 21 is inscribed to indicate price. Along the length of the cylinder are a number of these tables or 55 scales of prices, and one or the other of these is consulted according to the unit charge or price per pound of the commodity. For facilitating reading the chart it is convenient to employ at each side an elongated 60 cylindrical lens 26 which extends the whole length of the chart and magnifies the numbers. Along the bottom of the frame is shown a fixed scale 27 of basic prices. The operation is to select on the price scale 27 65 the figure indicating the price per pound of

the commodity, and by examining directly above this the magnified view of the proper scale is found opposite to the index line 25, a reading which constitutes the total price of the commodity or article being sold.

It is obvious that the set of inscriptions seen by the salesman at the left and shown in Figs. 2 and 4 would upon a half revolution of the cylinder stand in inverted position before the customer. This set of numbers, therefore, is not only inverted for the customer, but gives the wrong readings or results, so that the same is of no use at that side of the apparatus, but on the contrary a distinct detriment in the confusion it would tend to produce in reading a second and properly located set or system of numbers. In such and other cases, it is of value to have two separately viewable tables or scales, and this can be done without confusion by the present invention.

According to the present invention I inscribe upon the movable chart two superposed sets of inscriptions of optically dissimilar kinds, for example, of dissimilar or complementary colors. By superposed I mean that one set of inscriptions is printed or impressed upon the chart in proper position, arrangement and size without respect to the other set, and then the other set likewise printed over the same chart surface without respect to the first set. Sometimes the numbers or markings of one set may fall between those of the others, or sometimes directly one over the other, as seen in Figs. 4, 7 and 8. With such a chart in such a measuring apparatus I am enabled to combine a suitable correcting means such that one set or system of tables is apparent or visible from one point or side, and the other set from another point or the opposite side, or the two sets successively or selectively from the same point.

Such being the general characteristics of the present invention, I will now describe the preferred mode of embodying the same in practical form.

A convenient mode of providing the duplicate or superposed sets of readings or tables of optically dissimilar kinds is to print the system in two distinctive, opposite or complementary colors, and for the sake of illustration the colors red and green may be chosen, since they are practically complementary for the purposes of the present invention. In combination with such a two-color chart, this invention provides correcting means, preferably in the form of optical screens, which may consist simply of colored glasses corresponding with the selected colors red and green, and so arranged that the persons at the opposite sides will view the chart by light of the selected complementary colors, respectively.

Thus, referring to the perspective dia-

gram Fig. 4, a set or system of numerals 21^r is shown in full lines, representing a red printing color, while in dotted lines representing green is a duplicate system of numerals 21^g. The latter are, in the illustrated employment of the invention, relatively inverted, and are spaced away from the same numbers on the other system, namely, approximately 180° therefrom. If now, with this arrangement we can render the green numerals easily visible or apparent to the salesman at the left, while the red numerals are substantially invisible or non-apparent, and at the opposite side can render apparent the red numerals only, then without confusion or inconvenience the persons at the two sides will each perceive the same reading, namely, 5, thus attaining the object of the present invention.

To secure this result it is only necessary, according to this invention to provide that the salesman at the left shall view the chart with green light, and the customer at the right view it with red light; it being presupposed that the chart itself is printed on white paper or material. A simple manner in which to accomplish this is to employ a plate of green glass 23^g for the glass 23 at the left, and a plate of red glass 23^r for that at the right, within the respective hoods or frames 22, and as indicated by the reference numerals in Figs. 2 and 3. The effect of this is that whether daylight be used, or the special lamps 24, the observer at the left for example, is able to see the chart only by reflected light which has been twice transmitted through the medium, screen or glass plate 23^g. This apparently colors the white background of the chart to a green color, and the green printed numbers 21^g, being of an appropriate shade, blend and disappear so that the observer sees only the red system of numbers or scales; and the converse is true at the opposite side, the customer, through the red glass, seeing only the green colored inscriptions of the chart.

The optical principles of this result are made clear on Figs. 5 and 6. On Fig. 5 a portion of the chart 20 is shown, having white, green and red areas. In front stands the green color-screen 23^g. The action of a green glass is to shut off the transmission of rays of light other than green. Any white light, therefore, from the chart is converted into green as it passes through. The green light from the green areas passes through the screen without change, whereas the light from the red areas, having no green component, is wholly cut off at the glass plate. The observer, therefore, at the exterior sees only an even color everywhere, excepting for the red portions of the chart, which send no light to his eye, and therefore appear black. Analogously, Fig. 6 shows how the red portions of the chart blend with the background

when seen through the red glass, whereas the green portions stand out as black lines.

Figs. 7 to 10 illustrate these results on an enlarged scale. In Figs. 7 and 8 the vertically shaded lines indicate red color, and the slanted ones green color. Taking Fig. 7, for example, we have superposed numerals 5 upright and 35 inverted, the former red, the latter green. This is what the salesman would see at the left if there were no screen and he were able to see the chart by white light. The effect of employing the green screen 23^g, however, is, as shown in Fig. 9, to practically erase the green numeral 35, whereas by contrast the red numeral 5 stands out boldly in black. The more perfect and correct the colors selected for the printing and for the screens, the more perfect will be the result, and inaccuracies will tend to introduce a slight indication of the undesired numeral, without, however, spoiling the desired effect. At the opposite or front side the purchaser would see, as in Fig. 8, the upright numeral 5 in green and the inverted numeral 35 in red, but being compelled to view this through a red screen, he only observes the numeral 5 standing out in black contrast. Thus, both the salesman and the purchaser are advised that the price of the article is 5.

It is convenient to provide not only the price table system 21 on the chart, but also a weight table 28, which for convenience may be printed in type of different size and located at the center as shown in Fig. 2.

Without my invention two of such weight scales, relatively inverted, might be placed side by side, but this would require at each side a mask to conceal the inverted one, thus involving an unsightly and unsymmetrical complication; which is wholly done away with by this invention, by which the duplicate inverted weight scales are printed one on top of the other in the opposite colors, red and green, dispensing with any mask, and also gaining considerable space and enabling additional price scales to be added to a chart of given length.

In lieu of printing first a green system on the chart, and then a red one, one might be separately printed on a separate transparent paper and wrapped about the other.

Instead of providing the colored glass plates 23^g and 23^r in the hoods 22, respectively, the same result may be accomplished in many other and equivalent ways. For example, as shown in Fig. 11, a layer 31 of the color red or green may be attached or coated on the lens, or the lens itself might be of glass of the proper color. Or, as in Fig. 12, a small liquid tank may be provided by means of a glass plate 32 spaced away from the lens with peripheral walls 33, the tank being filled with a liquid of 130

the appropriate color. Anilin dyes constitute suitable colors, and a red and green dye should be selected which are opposite or complementary in the sense that each substantially excludes the passage of light of the other color. In the Fig. 11 modification the chart may be printed with a red or green dye or ink of this kind, and the lens coated with a layer of the same material held in place by gelatin or other suitable vehicle. The liquid tank of Fig. 12 permits the anilin color to be increased or decreased in strength or depth to adjust it to the purposes of the invention.

15 Instead of placing a screen between the eye and the chart, a similar result may be obtained by brightly illuminating the chart by colored light. Thus, as in Fig. 13, the green screen 23^r is placed between the lamp 24 and the hood 22. In effect the white parts of the chart are thereby colored up to a green color sufficiently matching the green printed numbers to render them invisible, whereas the red printed numbers 25 will stand out prominently as black. At the opposite side a red screen 23^r similarly placed will give analogous results; and in some cases the color screen at one side might be wholly omitted if the chart were printed vividly in one color and palely in the other color, so that at one side by ordinary light and at the other side by colored light the proper system or set of chart numerals would be relatively more apparent than the 30 other. The red and green screens 23^r and 23^g with their lamps may obviously be at the same side, enabling one or the other to be put into operation, in the case of two separate sets of inscriptions viewable selectively by the salesman.

35 It will thus be seen that I have described one form of measuring apparatus, namely, a weighing machine of a suitable type, the same embodying the principles and attaining the objects and advantages of the present invention, but since many described and illustrated matters of form, arrangement, combination, details and other features may be variously modified without departing 45 from the underlying principles, it is not intended to limit the invention to such features excepting as specified in the appended claims.

50 It will be noted that I have illustrated several of many forms which the invention may assume. It should be noted that many of the claims are generic if properly construed. For example in employing the expression "viewable by different lights" in the claims I do not use the word lights in the sense of lamps but rather in its broader physical sense, meaning: that form of radiant energy which is capable of acting upon the eye in such a way as to make visible 55 the object from which the light comes

either directly or by way of reflection. By way of further example the term "color filter" employed in the claims is intended to include a colored translucent element between the chart and the observer, or a similar element between the lamp and the chart, or the colored globe of a lamp, or other variations within the scope of the invention.

What is claimed is:

1. An automatic weighing machine of the type having a rotatable cylindrical chart viewable from opposite sides, the same comprising said chart, the same printed with duplicate sets of tables by complementary colors, as red and green, in combination with optical screens in front of said chart at the two sides thereof, the same having colors corresponding respectively to said colors, whereby one set of tables is apparent to an observer at one side and the other set at the other side.

2. A measuring apparatus comprising measuring means, a chart inscribed with superposed sets of inscriptions of optically dissimilar kinds, the same viewable simultaneously from different viewpoints and mounted and connected so as to be shiftable by the action of the measuring means, in combination with an optical correcting means whereby one set of such inscriptions is predominantly apparent from one viewpoint and another set from another viewpoint.

3. A measuring apparatus comprising measuring means, a chart inscribed with superposed sets of inscriptions of optically dissimilar kinds, the same viewable simultaneously from different viewpoints and mounted and connected so as to be shiftable by the action of the measuring means, in combination with dissimilar optical screens located at different points such that one set of such inscriptions is predominantly apparent through one screen from one viewpoint and another set through another screen from another viewpoint.

4. In or for a measuring apparatus, a calibrated printed chart having a tabular set of inscriptions printed in one character or color, and superposed on the same a second or separate tabular set of inscriptions printed in a dissimilar character or color and in a predetermined relation to the first set.

5. A measuring apparatus comprising a calibrated chart viewable by different lights and printed with two superposed systems of inscriptions of opposite colors, in combination with means whereby the chart may be exposed to view by lights of different colors.

6. A measuring apparatus comprising a calibrated chart relatively shiftable in accordance with the quantity measured and viewable by different lights and printed

- with two superposed systems of inscriptions of opposite colors, in combination with optical screens of corresponding colors adjacent the chart.
5. 7. A measuring apparatus comprising a calibrated chart viewable by different lights and printed with two superposed systems of inscriptions of opposite colors, in combination with an elongated lens and a color screen through which said chart is viewable.
10. 8. A measuring apparatus comprising a chart viewable by different lights and printed with two superposed systems of inscriptions of opposite colors, in combination with an elongated lens and a color screen through which said chart is viewable, said screen consisting of a transparent tank containing dilute color material corresponding to one of those with which the chart is printed.
15. 9. A measuring apparatus calibrated chart having a set of inscriptions printed in one color and superposed over the same area a second set of inscriptions printed in a dissimilar color.
20. 10. A weighing apparatus comprising a weight-shifted chart viewable by different lights and printed with superposed tables in opposite colors, and means for exposing the chart to lights of different colors.
25. 11. A measuring apparatus comprising in combination, a chart, an index cooperative with said chart, said chart and index being relatively movable, said chart being provided with a plurality of superimposed differently colored series of progressive indications, and means comprising a color filter for causing one of said series to become predominantly visible with respect to said index.
30. 12. A measuring apparatus comprising in combination, a calibrated chart having a plurality of superimposed differently colored series of progressive indications, means comprising a color filter for causing one of said series to become predominantly visible, and means comprising a color filter for
- causing another of said series to become predominantly visible.
13. A measuring machine comprising in combination, a support, a chart movably mounted thereon, and displaceable in accordance with the quantity measured, said chart being provided with a plurality of differently colored series of progressive indications, and means comprising a color filter for causing one of said series to become predominantly visible.
14. A chart provided with a plurality of superimposed differently colored series of progressive indications, each of said series being relatively displaced with respect to the remaining series in the direction of progression.
15. A chart provided with a plurality of superimposed differently colored series of progressive indications, the indications of each of said series being relatively displaced with respect to similar indications of the remaining series in the direction of progression.
16. A weight-controlled measuring apparatus having a printed chart having a tabular set of inscriptions printed in one color, and superposed on the same a corresponding tabular set of inscriptions printed in a dissimilar color and in a predetermined relation to the first set, and means comprising a color filter for causing one of said sets to become predominantly visible.
17. A weight-controlled measuring apparatus having a relatively movable printed chart having a tabular set of inscriptions printed in one color, and superposed on the same a corresponding tabular set of inscriptions printed in a dissimilar color and in a predetermined relation to the first set, and means comprising a color filter for causing one of said sets to become predominantly visible.
- In testimony whereof, I have affixed my signature hereto.

CHRISTIAN BERGER.
